United States Patent Office.

NATHANIEL F. PAGE, OF RUTLAND, VERMONT, ASSIGNOR TO HIMSELF
AND ELIJAH WHITNEY, OF THE SAME PLACE.

Letters Patent No. 70,886, dated November 12, 1867.

IMPROVED RAILWAY CHAIR.

The Schedule referred to in these Letters Patent and making part of the same.

TO ALL PERSONS TO WHOM THESE PRESENTS SHALL COME:

Be it known that I, NATHANIEL F. PAGE, of Rutland, in the county of Rutland, and State of Vermont, have invented a new and useful improvement in Railway Chairs; and I do hereby declare the same to be fully described in the following specification, and represented in the accompanying drawings, of which—

Figure 1 is a top view, and

Figure 2 an end elevation of a chair provided with my invention.

The object of my invention or improvement is to enable the rail or rails to be readily removed from the main body of the chair without the necessity of drawing the spikes by which such body is fastened to the sleeper.

For this purpose I construct the main or body part A of the chair with two stationary lips *a b*, arranged so far apart as to enable the rail B to be dropped between them, or to be raised from between them, as circumstances may require. One of the lips is to fit to the upper surface of the flange of the rail, the other being to fit upon and project over the base *c* of a separate cap, C, formed and arranged with reference to the rail, in manner as exhibited. After the rail or rails may have been placed within the part A of the chair, the cap C is to be slid into place underneath the lip *b*, and may be held in position by means of keys *d d* going down through the lip *b* and notches *e e*, made in the edge of the cap, in manner as shown in Figure 3, which is a top view of the said cap. Each rail, B, may be recessed on its opposite sides, as shown at *f f*, in Figure 4, which is view of one of such rails, such recesses being to receive corresponding projections *g g*, extending from the upper side of the bottom plate of the chair, the whole being as shown in Figure 5, which is a top view of the part A, and also in Figure 6, which is a transverse section of such part, A. Furthermore, the recess under the lip *b*, instead of being in the same plane with that surface of the part A on which the rail rests, is inclined or is arranged at an obtuse angle with reference thereto, in manner as represented. This causes the cap C, while being drawn by the keys toward the rail, to descend also a little, so as to take a firm bearing on the rail flange.

I claim as my invention the combination as well as the arrangement of the cap C with the part A, made with the two lips *a b*, to receive the rail and the cap, substantially as specified.

I also claim the arrangement of the recess of the lip *b*, at an obtuse angle with the rail-supporting surface of the chair, such chair being provided with two lips, *a b*, and a cap, C, as set forth.

NATHANIEL F. PAGE.
